UNITED STATES PATENT OFFICE.

JOHN DRAPEAU AND ADOLPHUS DRAPEAU, OF RIVER ROUGE, MICHIGAN.

TOBACCO PIPE.

Application filed March 1, 1924. Serial No. 696,278.

To all whom it may concern:

Be it known that we, JOHN DRAPEAU and ADOLPHUS DRAPEAU, citizens of the United States, residing at River Rouge, in the county of Wayne and State of Michigan, have invented new and useful Improvements in Tobacco Pipes, of which the following is a specification.

One of the objects of our said invention 10 is the provision of a tobacco pipe equipped with means whereby the bowl may be scraped or cleaned conveniently for the removal of ashes and other débris from the bowl.

15 Another object is the provision of a tobacco pipe stem embodying simple and efficient means for practically eliminating the liability of saliva finding its way through a stem to a pipe bowl and giving rise to the 20 objectionable condition which exists when the tobacco in the bowl is rendered moist by saliva.

To the attainment of the foregoing, the invention consists in the improvement as 25 hereinafter described and definitely claimed.

In the accompanying drawings, forming part of this specification—

Figure 1 is a longitudinal central section of a tobacco pipe constructed according to 30 our invention.

Figure 2 is a section taken through the bowl of the pipe in the plane indicated by the line 2—2 of Figure 1.

Figure 3 is an inverted plan view showing 35 the handle in normal position and adapted to serve as a match scratcher.

Similar numerals of reference designate corresponding parts in all of the views of the drawings.

40 The stem 1 of our novel pipe may be joined at 2 in any appropriate manner to the shank 3 of the bowl 4 or may be formed integral with the said shank 3 without affecting our invention. The stem 1 and shank 3 are provided with the usual coincident bores 5 and 6 as illustrated.

45 In accordance with one part of our invention the bowl 4 is provided in its bottom with a central opening lined by an appropriate bushing 7 as illustrated. Journalized in the said lined aperture is a short shaft 7^a on which are fixed three (more or less)

cleaning or scraping blades 7^b which are formed of spring steel or other appropriate material and are opposed to and movable 55 against the wall of the bowl 4 at the bottom and side thereof. The lower exterior portion of the bowl is recessed at 8 and in the said recess is removably housed a handle 9 which is hingedly connected at 10 to the 60 shaft 7^a. The handle 9 is adapted to swing into the recess 8 so as to normally afford no projection from the pipe. When, however, it is desired to clean or scrape the bottom and side of the interior of the bowl 4 it is 65 simply necessary to swing the handle 9 down into alignment with the shaft 7^a when through the medium of the widened end portion of the handle 9, the shaft 7^a may be turned strongly about its axis when as will 70 be readily observed the blades on the shaft 7^a will be moved in the bowl and against the bottom and side thereof to remove ashes and other débris which can be readily dumped from the bowl, thereby obviating the necessity of beating the bowl or using a match, penknife or the like to displace ashes from the bowl. It will also be noted that our improvement obviates the likelihood of the 75 bowl becoming too thickly caked. After 80 cleaning of the bowl in the manner described the handle 9 may be housed in the recess 8 of the pipe.

The wide free end portion of the handle 9 is advantageous because it affords an adequate hold for thumb and fore finger, and the wide handle is also advantageous because when knurled at its outer side as designated by 10^c in Figure 3, the handle 9 constitutes an advantageous match scratcher. 85 90

In accordance with another part of our invention, the rear portion of the stem 1 is reduced at 12 to receive a cap-like mouth piece 13 in the lower portion of the outer end of which is formed an aperture 14. 95 Also a chamber 15 is formed in the stem 1 at the rear end of the bore 5. In the rear end of the said chamber is a flanged bushing 16, and extending through the bore of the said bushing is a rod 17 smaller than said bore. At its rear end the said rod 17 is provided with a closure disk 18 and on the forward portion of the rod is an enlargement 19, between which and the bushing 16 is in- 100

terposed a spring 20 which serves to yieldingly hold the disk 18 against the outer end of the plug 16 so as to close the bore therein and the downwardly inclined mouth at the outer end of said bore. The spring moved valve 18 will manifestly open when smoke is drawn through the stem but will promptly close after each draft with the result that saliva will be prevented from reaching and 10 passing through the bore in the stem. This result is also contributed to by the arrangement of the aperture 14 in the lower portion of the end of the cap 13.

We have entered into a detailed description of the construction and relative arrangement of the parts embraced in the present and preferred embodiment of our invention in order to impart a full, clear and exact understanding of the said embodiment. We do not desire, however, to be understood as confining ourselves to the specific construction and relative arrangement of parts inasmuch as in the future practice of the invention various changes and modifications may be made such as fall within the 20 scope of our invention as defined in our appended claims.

Having described our invention, what we claim and desire to secure by Letters Patent, is:—

1. In a tobacco pipe, the combination of a bowl having an opening in its bottom and also having a recess in its underside in communication with said opening, a shaft journaled in the said opening, bowl cleaning means carried by the said shaft, and a handle hingedly connected to the shaft and swingable into and out of said recess. 30

2. In a tobacco pipe, the combination of a bowl having an opening in its bottom and also having a recess in its underside in communication with said opening, a shaft journaled in the said opening, bowl cleaning means carried by the said shaft, and a handle hingedly connected to the shaft and swingable into and out of said recess; the said handle having a rough outer surface adapted to serve as a match scratcher when the handle is disposed in said recess. 35

In testimony whereof we affix our signatures. 45

JOHN DRAPEAU.
ADOLPHUS DRAPEAU.
